HYDRAULIC PRECISION LATHE

Leo F. Collins, Seattle, Wash.

Application October 22, 1932, Serial No. 639,622

1 Claim. (Cl. 82—2)

This invention relates to improvements in lathes, and more particularly to lathes of the screw cutting precision type; it being the principal object of this invention to provide a lathe of the above character in which the movement of the cutter or tool is produced and controlled by hydraulically actuated mechanism.

More specifically stated, the present invention resides in the provision of a lathe in which the tool holding block is mounted for movement under the individual control of a main feed hydraulic cylinder and a cross feed hydraulic cylinder; the said cylinders including their piston assemblies, connecting tubes for application of the fluid pressure medium and certain novel control valves whereby the direction of flow and amount of flow may be finely adjusted so as to positively and accurately control the movement of the tool.

Another object of the invention is to provide an automatic hydraulically actuated means for offsetting the tool or cutter from the work for the return stroke and to make this reversible so as to adapt it for either external or internal work.

Other objects of the invention reside in the details of construction of the various parts, in their combination and mode of operation, as will hereinafter be more fully described.

In accomplishing these and other objects, I have provided the improved details of construction, the preferred forms of which are illustrated in the accompanying drawings, wherein—

Fig. 1 is a front elevation of a lathe equipped with mechanism in accordance with the present invention.

Fig. 2 is a plan view of the same.

Fig. 3 is a cross section, taken substantially on the line 3—3 in Fig. 1.

Fig. 4 is a longitudinal sectional view of the main feed cylinder.

Fig. 5 is an end view of the same.

Fig. 6 is a view diagrammatically illustrating the hydraulic control cylinders, control valves and piping connections.

Fig. 7 is a longitudinal section of one of the feed control valves.

Fig. 8 is a cross section on line 8—8 in Fig. 7.

Fig. 9 is a longitudinal section of the reversing valve.

Fig. 10 is a cross section on line 10—10 in Fig. 9.

Fig. 11 is a longitudinal section of the screw cutting control valve.

Fig. 12 is a cross section of the same taken on line 10—10 in Fig. 11.

Fig. 13 is a horizontal section of the cross feed cylinder.

Fig. 14 is a sectional view of the automatic cut off valve.

Fig. 15 is a side view of the feed adjustment.

Fig. 16 is a plan view of the same.

Referring more in detail to the drawings—

The present lathe comprises the usual bed 10 frame structure 1 supported by legs or end frames 2—2 at a suitable working height. At one end is the usual head stock 3 with stepped pulleys 4 for obtaining various driving speeds and at the opposite end is the tail stock 5. The pulley shaft 15 of the head stock carries the face plate 6 with a chuck 7 for mounting the work, and the tail stock carries a center 8 which may coact with parts 6 and 7 to mount the piece to be worked on.

Slidably mounted on the bed frame for travel 20 longitudinally thereon is a carriage 10, and slidably mounted on this carriage for travel in a direction transversely of the bed frame is the cross feed plate 11 on which the tool mounting block 12 is fixed. The cutter or tool, as designated at 25 13 is adjustably mounted in a support 14 adjustable on the block in the usual manner to provide for its being set for operation on pieces of various shapes.

As will be best seen in Fig. 3, the carriage 10 is 30 held in proper alignment by the provision of inverted V-shaped grooves 15 in its under side which slidably receive correspondingly shaped and parallel ribs 16 on the bed frame. Clips 17 attached to the carriage slidably engage beneath 35 flanges 18 of the frame to prevent any upward displacement of the carriage. This carriage rigidly mounts the main feed cylinder 19 which is disposed parallel with and adjacent the forward side of the bed plate as seen best in Figs. 40 1 and 2. Within the cylinder is a piston 22, as seen in Fig. 4, to which is fastened a piston rod 23 slidable through a packed gland 24 in the cylinder head 26. The outer end of the rod 23 is fixed to a bracket 25 that is rigidly fastened to 45 frame 1. Opposite end heads 26 and 27 of the cylinder 19 mount two parallel manifolds 28 and 29 of tubular character from which pipe connections are made with a regulating valve B. As seen in Fig. 6, pipe sections 141 and 143 join 50 manifold 28 with valve B and pipes 160, valve housing F, pipe 161 and 167 join manifold 28 with valve B at a point diametrically opposite the point of entrance of pipe 143.

Pressure medium supply and outlet pipes 32 /

and 33 have ends fixed in bracket 25 and have their opposite end portions slidably extended through packed glands 35 and are telescopically contained in the manifolds 28 and 29, respectively, so that communication between the pipes and manifolds will be maintained for all positions of movement of the cylinder 19 and carriage in its travel lengthwise of the machine.

A pressure medium supply pipe 40 connects 10 with pipe 32 adjacent the bracket 25 and likewise an outlet or exhaust pipe 41 connects with pipe 33.

The cross feed cylinder 20 is rigidly secured to the slide 11 as seen in Fig. 3 and pressure medium is admitted thereto under control of a valve A 15 from the supply through the manifold 28. As seen in Figs. 6 and 13, the cylinder 20 contains a piston 45 and this has two hollow or tubular piston rods 46 and 46a fixed thereto and extending through the inner end of the cylinder where 20 they are fixed against movement by a connection presently described, with the main frame. The piston rod 46 extends through the piston in open communication with the chamber at the outer end of the cylinder, and piston rod 46a has a 25 port 46b opening into the cylinder at the other side of the piston.

Control valve A is connected at diametrically opposite points of its upper end with the manifolds 28 and 29 respectively; one connection comprising the pipes 148 and 168, as seen in Fig. 6, and the other connection comprising pipes 142 and 141. The valve A is also connected at diametrically opposite points of its lower end with the hollow piston rods 46 and 46a respectively; 35 one connection comprising pipes 146 and 147, and the other comprising pipes 144 and 145.

The valves A and B may be manipulated to regulate the flow of pressure medium to the cylinders 19 and 20 to thereby control the rate of 40 travel of the cutter. These two valves are of like construction and are of the type illustrated in Figs. 7 and 8 wherein 101 designates a cylindrical valve housing provided at its upper end with diametric ports 102 and 103 and at its lower end 45 with diametric ports 104 and 105. Valve A receives the pipes 142, 148, 144 and 146 respectively in the ports 102, 103, 104 and 105. Valve B likewise receives the pipes 157, 143, 153 and 152 into 50 these ports.

In the cylinder 101, is revolvably mounted a helical or screw shaped core 106 provided with islands 107 (in Fig. 8). The top of the core is provided with a shank 108 and an operating handle 109. The core is axially held in place by a 55 cover 110 screwed onto the cylindrical body 101. From the above it will be apparent that when islands 107 register with ports 102-103 the valve will be inoperative, and it will also be noted that if the core is rotated that the pressure medium 60 may be made to pass from port 102, which will now be considered the intake port, to port 104 or port 105 depending on the rotation on the core 106, for example in Fig. 7 the core being rotated as shown the pressure medium will flow from 65 port 102 to port 104 and a returning pressure medium will enter port 105 and pass up to port 103. If the core is rotated in the opposite direction, the pressure medium will pass from port 102 to 70 105 and returning pressure medium will enter at 104 and pass to 103.

Referring now to the means of connecting the piston rods 46-46a to frame 1—

The forward ends of these rods are mounted on an eccentric 58 supported at its ends by pivots 61 in a bracket 52 fixed to the frame 1. On the

eccentric a lever 53 is fixed, the outer end of the lever being pivotally connected to the end of a piston rod 54 attached to a piston 55 operable in a cylinder 52 supported from frame 1 as seen in Fig. 3. Opposite ends of this cylinder have pipe connections 155-156 leading respectively to upper and lower ports of a reversing valve D connected by pipes 155'-156' with pipes 152 and 154. The purpose and operation of this valve will presently be described in connection with the tool 10 offsetting operation. There is also a reversing valve C interposed in the connections with valve A, and it has a connection 146' leading to pipe 146, a pipe 158 leading to pipe 145, and connections 146a and 158a leading to opposite ends of 15 a cylinder 138 which, as seen in Fig. 14, contains a piston 137 connected by rod 136 to a valve 135 which controls flow of medium through valve F in the pipe connection between manifold 29 and valve B.

The valve F consists of a casing connected at opposite ends with pipes 149 and 161 and having a dividing wall 162 provided with a passage seating valve 135. Pressure may enter the cylinder 138 from pipe 149 to act on piston 137 to unseat 25 the valve to permit flow to pipe 161.

These reversing valves C and D are of the type shown in Fig. 9. Each consists of a hollow cylindrical body 111 provided with ports 112-113 at diametric points in its upper end and ports 30 114-115 at diametric points in its lower end. The valve D receives the pipes 115'-155, 155' and 156 respectively into these ports 112, 113, 114 and 115. Valve C receives the pipes 146'-146a, 156 and 158a, respectively, into these ports in the 35 order enumerated.

Within the casing 111 a core 116 is rotatably mounted and this is provided with holes 117-118 and helical passages 119-120 passing halfway around the core, as shown. Top of the core is provided with a shank 121 and handle 122 and is held in place axially by cover 123 screwed to the body 111 of the valve. The core 116 being turned in the position shown (port 112 being considered the intake port) the pressure medium will pass from port 112 through passage 119 to port 114 and the returning pressure medium will pass from port 116 through passage 120 to port 113. When core 116 is rotated one quarter turn so hole 117 registers with port 112-113, hole 118 with 50 ports 114-115 shown in the dotted lines, the pressure medium will pass from port 112 through hole 117 to port 113 and a returning pressure medium will pass from port 114 through hole 118 through port 115.

For screw cutting operations the machine is operated under control of a screw cutting valve E, shown in detail in Figs. 11 and 12. This valve is interposed in the connection between pipe 149 and valve B as seen in Fig. 6. The valve housing 60 is connected at its upper end by pipe 159 with pipe 149 and at its lower end by pipe 158 with pipe 161.

This valve comprises a body 124 with a cored out chamber 125. The bottom of the body is 65 provided with a port 125a and the side with a port 125b which, respectively, receive the pipes 158 and 159. The top and bottom of the chamber are turned out as shown at 126 and 127 to receive a hollow sleeve 128 (see Fig. 12) pressed firmly in 70 place. This sleeve is provided with longitudinal, narrow slits 129. On the inside of the sleeve 128 is rotatably mounted a hollow cylindrical core 130 the bottom of which is open and the top closed and provided with a shank 131 to which is 75

- secured a worm gear 132 which coacts with a lead screw 27 of the turning lathe. The walls of this cylindrical core are provided with slits 133 which will register with slits 129 with the sleeve 128 when properly turned, as shown in Fig. 12, and in which position the pressure medium may pass from port 125a into hollow core 130 through slits 133 of the core, slits 129 of the sleeve 128 into chamber 125 and to port 125b.
- 10 Briefly referring again to the piping diagram shown in Fig. 6, 141 is a pipe connecting from manifold 28 and branches into two pipes 142 and 143, pipe 142 connecting with inlet port 102 of valve A which is of the type shown in Fig. 7. 15 Port 104 connects with pipes 144 and 145 to hollow piston rod 46a. Port 105 connects with pipes 146 and 147 to hollow piston rod 46, and port 103 connects with pipes 148, 149 and 150 to manifold 29. Pipe 143 connects with port 102 of valve B which is of the same type shown in Fig. 7. Port 104 as shown in Fig. 7, connects with pipes 151 and 152 to right hand end of carriage cylinder 19. Port 105 connects with pipes 153 and 154 to the left hand end of the cylinder 19.
- 20 25 The reverse valves C and D, as shown in Fig. 6, are of the type shown in Fig. 9 and are connected in the pressure circuit as shown in Fig. 6. The screw cutting valve E of Fig. 6 is the same as the valve shown in Fig. 11. The valve F with its 30 control is the same as the valve shown in Fig. 14. The reference numerals for the ports of valves C, D, E and F are the same as those used in the corresponding Figs. 9, 10, 11, 12 and 14.
- 35 In the use of the machine for all ordinary turning, or when the carriage is moving longitudinally with the lathe, only valve B is used. Assuming the core of the valve to be in the same general position as shown in Fig. 7, the pressure circuit is as follows—
- 40 The pressure medium enters pipe 40, passes through pipe 32 into manifold 28 through pipes 141 and 143 to port 102 of valve B, through the valve to port 104 to pipes 151 and 152 into right hand end of cylinder 19, causing it, and consequently the entire carriage with all its attachments such as piping valves, etc., to move to the right. The pressure medium in the left hand end of the cylinder 19 will be forced into pipes 154 and 153 to port 105 of valve B, through the 45 valve to port 103 to pipes 157 and 161 through valve F through pipes 162 and 149 and 160 to manifold 129 and back to the source. Upon reaching the end of the cut, valve D is opened, thereby causing hole 117 to register with ports 112 50 and 113, or at an angle of ninety degrees from the position shown in Fig. 9, so the pressure medium will pass from pipe 151 to port 112 through the valve to port 113 through pipe 155 into the inner end of the cylinder 56 turning the lever 55 53 so as to rotate the eccentric 50 in such a manner as to pull the piston rods 46—46a inwardly pulling piston 45 and cylinder 20 inwardly, carrying with it the cross feed with the tool a slight distance away from the work. The reason for 60 the cylinder moving with the piston is due to pressure medium being trapped between the piston 45 and the inner end of cylinder 20. The tool being relieved from the work, the valve B is reversed, in which case the pressure medium 65 passes from port 102 through the valve to port 105 through pipe 153 and 154 into the left hand end of the cylinder 19 returning the carriage with the tool to the left, thus returning the tool to

the beginning of the cut. Valve D is now reversed allowing the tool to come in contact with the work. For internal turning, valve D is turned in the reverse direction from that described above causing the reverse action of piston 55 and lever 53 which in turn pulls the tool away from the cut.

Assuming it is desired to operate the cross feed such as turning the face of a disk, valve A is used, the rest remaining closed. The valve A being turned in the reversed direction from that shown 10 in Fig. 7 the pressure medium will pass from manifold 28 through pipes 141 and 142 to port 102 of valve A, through the valve to port 105, through pipes 146 and 147 into hollow piston rod 46 into the outer end of cylinder 20 causing it to move 15 outward which in turn feeds the tool inwardly toward the center of the lathe; the cylinder 20 and the tool being located on the opposite side of the work. Upon reversing valve A, or to the position shown in Fig. 7, the reverse action takes place 20 and the tool is returned to the outside edge of the work.

Supposing it is desired to turn thread, valves A and C are operated so that as the pressure medium passes from valve A by either pipe 146 25 to port 112 of valve C, or through pipes 144—156 to port 115 of valve C; in either case the valve C is set so that the pressure medium passes through port 113 into the left hand end of cylinder 138 closing the valve F, as seen in Fig. 14. 30 As the lathe is set in operation and the lead screw set for the proper thread, worm gear 132 of valve F will be rotated turning the core of the valve so as to permit the returning fluid to valve B to pass from port 103 through pipe 157 and 158 35 to the bottom of valve E through the core from the sleeve to outlet port 125b through pipe 159—160 to manifold 29. As soon as this valve is set into operation the motion of the carriage moves the valve E with it, and this relative movement 40 between the carriage and the lead screw will turn the worm gear 132 in the opposite direction so as to close off the pressure medium. As these two movements are continued a general opening or balance of valve E will be obtained causing the 45 carriage to move at the proper rate for cutting of the thread desired.

Having thus described my invention, what I claim as new therein and desire to secure by Letters Patent is—

50 A lathe comprising, in combination, a bed frame, work supporting means in the frame, a carriage movable longitudinally along the frame, a slide on the carriage movable transversely of the frame, a work engaging tool mounted on the slide, a cylinder fixed to the carriage and extending longitudinally of the frame, a cylinder fixed to the carriage and extending transversely of the frame, a piston in each cylinder, the piston of the first cylinder having a fixed connection with the frame, an eccentric mounted by the carriage and connecting the piston of the second cylinder therewith and individual means for controlling an application of pressure medium to each cylinder for affecting its movement in either direction at a controlled speed and a hydraulic cylinder connected in the said last mentioned means and having a piston automatically operable incident to reversal of direction of flow in the first cylinder to rotate the eccentric to move the slide 70 to offset the tool from the work.

LEO F. COLLINS.
